RAIL FLAW DETECTOR MECHANISM

Harcourt C. Drake, Hempstead, N. Y., assignor to
Sperry Products, Inc., Brooklyn, N. Y., a cor-
poration of New York

Application March 9, 1935, Serial No. 10,143

7 Claims. (Cl. 175—183)

This invention relates to rail flaw detecting apparatus of the type employed in the Sperry rail flaw detector car. Such flaw detection apparatus comprises passing of a heavy current through an electrical conductor to be tested so as to establish an electromagnetic field surrounding the conductor and then moving a pair of opposed induction coils along said conductor spaced a constant distance therefrom. When a flaw occurs the axis of the current is displaced and the said induction coils on encountering said displaced electromagnetic field will generate a differential E. M. F. which is then amplified and the amplified voltage is caused to operate a pen on the chart and cause a paint mark to be placed upon the rail in the region of flaw.

The current is led into the conductor by contact brushes and leaves the conductor by a second set of brushes, both sets of brushes being carried by a carriage which supports the detector mechanism between the two sets of brushes. It has been found that it takes some time after the current enters the conductor for the molecules to align themselves with the proper polarity relative to the polarity of the energizing current, and for this reason the said Sperry detector cars carry mechanism for preenergizing the rail. Such preenergizing arrangement is disclosed in applicant's Patent No. 1,944,930 granted January 30, 1934.

Reference to the said patent discloses that in order to obtain the desirable effect of preenergization it was necessary to employ a third set of brushes positioned ahead of the original inlet and outlet current brushes and supplied with current from an auxiliary generator. The present invention has for its principal object the provision of means whereby the same effect of pre-energization may be obtained at all times by the use of but a single generator instead of a main generator and an auxiliary generator as disclosed in the said patent.

Further objects and advantages of this invention will become apparent in the following detailed description thereof:

In the accompanying drawing,

Fig. 1 is a side elevation of a Sperry rail flaw detector car showing by a wiring diagram applicant's invention applied thereto.

Fig. 2 is a wiring diagram disclosing the form of preenergizing arrangement heretofore employed.

Referring to Fig. 1 of the drawing, there is disclosed a Sperry rail flaw detector car comprising the car body 10 within which is mounted

a generator G adapted to supply current to the rail to establish an electromagnetic field surrounding the same. The current from generator G may be passed into and out of the rail by means of sets of brushes 11 and 12. Said set of brushes 12 and an auxiliary set of brushes 13 may be carried by a current brush carriage 14, said carriage being supported on the car body 10 by means such as cables 16 and springs, not shown, which normally maintain the current brush carriage in raised or ineffective position. When it is desired to lower said carriage into engagement with the rail, fluid pressure such as compressed air is supplied to cylinders 17 to depress piston-rods 18, said piston-rods being connected to the current brush carriage so that said carriage is lowered against the action of the retractile springs. The current brush carriage may be adapted to ride along the rails on means such as flanged wheels 19. The set of brushes 11 may be raised by means of a cable 16' and a spring, not shown, and may be lowered by supplying the compressed air to an additional cylinder 17' to depress piston-rod 18'. The source of compressed air is connected to said cylinders 17 and 17' so that all of said brushes are raised and lowered simultaneously.

Current is normally supplied from the generator G to front brushes 11 through the rail R to rear brushes 12 and returned to the generator. An electromagnetic field surrounding the rail is thus built up and said field is uniform as long as there are no flaws. When flaws occur there is a distortion of the electromagnetic field in the region of the flaw and such distortions are designed to be detected by induction means which may comprise a pair of opposed induction coils 20 supported in a housing 21 carried by a detector carriage 22 which is designed to be supported on the current brush carriage 14 for movement independent thereof by means such as loose-fitting bolts 23 and springs 24 constituting limited universal joints. The detector carriage 22 may be supported on the rail surface by means such as rollers 25, and the current brush carriage may be supported on the rail by means such as flanged wheels 19. It will now be seen that as the car travels along the rail R the inductive means 20 are maintained a constant distance above the rail surface and will normally cut a constant number of lines of force. When a region of flaw is encountered, one of the coils will cut a different number of lines of force and there will be generated a differential E. M. F. which, after being amplified, may be caused to

operate indicating means such as pens operating on a moving chart and rail marking means such as a paint gun.

By reference to Fig. 1 it will be seen that the detector carriage 22 is positioned as far removed from the front current brushes 11 as the car construction will permit. This is desirable because, as stated in the introduction to this specification, a certain time elapses before the current passing through the rail can align the molecules of the rail so that their poles are homogeneously arranged. This has been found to facilitate greatly the detection of flaws. The positioning of the front current brushes 11 so far ahead of the rear brushes 12 creates certain difficulties which will be apparent from a study of Fig. 1 wherein an insulated joint is shown at J. This means that as soon as the front current brushes 11 have passed the insulation of joint J, no current is passing through rail R and the flaw responsive means is ineffective to discover any flaws in that portion of the rail between the point where the detector carriage is positioned when brush 11 passes joint J and the said joint. This is a substantial distance and equivalent to almost the car length.

One solution of the above difficulty is disclosed in the said Drake Patent No. 1,934,930 and is shown in Fig. 2. In this form of the invention, an auxiliary generator G' is provided for performing the preenergizing function between brushes 11 and brushes 13. The normal current is supplied by generator G between brushes 13 and brushes 12. Thus, when front brushes 11 have passed an insulated joint J or a joint of high resistance which causes a sharp drop in the current passing over brushes 11 to brushes 12, the flaw responsive mechanism is not affected because generator G continues to supply current between brushes 13 and brushes 12. This solution of the problem, however, requires the use of an auxiliary generator G' and it is the object of the present invention to perform the same function with but a single generator.

This solution of the problem is disclosed in Fig. 1 wherein the current normally is supplied by generator G to front brushes 11 and passes to rear brushes 12 before returning to the generator. When, however, the brushes 11 pass an insulated joint J or joint of high resistance which causes the current to drop between brushes 11 and brushes 12, I provide means for rendering effective a flow of current from generator G through auxiliary front brushes 13 to rear brushes 12 and return to the generator. Since auxiliary front brushes 13 are close to the flaw responsive means 20, full current will pass between brushes 13 and brushes 12 until said brushes 13 pass the joint J, at which time the flaw responsive mechanism will have reached the joint bar B in which region no testing is performed in any case. I accomplish this result by placing in the circuit from generator G through front brushes 11 and rear brushes 12, a resistance S and an electromagnet 30 in parallel with the circuit through the brushes 11. Said resistance is of such magnitude that normally insufficient current passes through magnet 30 to enable it to attract an armature 31 against the action of a retractile spring 32, and the major portion of the current passes through brushes 11. However, when front brushes 11 pass an insulated joint or joint of high resistance all of the current is diverted through resistance S and magnet 30 so that sufficient current passes through the magnet to enable it to attract armature

31 and close a set of contacts 33. The closing of said contacts 33 closes a normally ineffective auxiliary circuit from generator G through said contacts, the armature 31, brushes 13, brushes 12, and return to generator. The contacts 33 also short-circuit resistance S so that the full current flows through brushes 13.

Since a certain amount of current flows through resistance S and magnet 30 when contacts 33 are open, there is current flowing through the rail in the region of the detector coils at all times, even in that interval when brushes 11 have just passed the joint J and before contacts 33 have closed. When brushes 13 have passed the joint the circuit through magnet 30 is interrupted and the current therein falls to such extent that retractile spring 32 opens the contacts 33. As soon as brushes 12 have passed joint J the current is immediately ready to flow from brushes 11 to brushes 12 by reason of the open contacts 33 which causes the main portion of the current to flow through brushes 11.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. In a rail flaw detector car, a source of electrical energy, means for establishing a circuit from said source through the rail, flaw responsive means cooperating with the energized portion of the rail, a normally ineffective auxiliary circuit including said source and extending through the rail in the region under test, and means whereby said auxiliary circuit is rendered effective when the current in said first circuit drops to a predetermined degree.

2. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit from said source and extending through the rail in the region of said flaw responsive means, and means whereby said auxiliary circuit is rendered effective when the current between said front and rear brushes drops to a predetermined degree.

3. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit from said source and extending through the rail in the region of said flaw responsive means, said auxiliary circuit including auxiliary brushes positioned between said front and said rear brushes, and means whereby said auxiliary circuit is rendered effective when the current between said front and rear brushes drops to a predetermined degree.

4. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit including said source and extending through the rail in the region of said flaw responsive means, said auxiliary circuit including auxiliary front brushes positioned closely adjacent said responsive means, and means whereby said auxiliary circuit is rendered effective when the current between said first named front brushes and said rear brushes drops to a predetermined degree.
5. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit through the rail in the region of said flaw responsive means, and means whereby said auxiliary circuit is rendered effective when the current between said front and rear brushes drops to a predetermined degree, said last-named means comprising a shunt circuit including a magnet, said auxiliary circuit including a pair of contacts and means normally maintaining said contacts open to render said auxiliary circuit ineffective, means whereby said magnet closes said contacts when the current in said main circuit exceeds a predetermined quantity, and a resistance in said shunt circuit for maintaining the current through said magnet below said predetermined quantity as long as the current in said main circuit exceeds a predetermined quantity.
6. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit through the rail in
- the region of said flaw responsive means, and means whereby said auxiliary circuit is rendered effective when the current between said front and rear brushes drops to a predetermined degree, said last-named means comprising a shunt circuit including a magnet, said auxiliary circuit including said magnet, a pair of contacts and means normally maintaining said contacts open to render said auxiliary circuit ineffective, means whereby said magnet closes said contacts when the current through said magnet exceeds a predetermined quantity, a resistance in said shunt circuit for maintaining the current through said magnet below said predetermined quantity as long as the current in said main circuit exceeds a predetermined quantity, and means whereby closing of said contacts to render said auxiliary circuit effective short-circuits said resistance.
7. In a rail flaw detector car, a source of electrical energy, a main circuit including said source and front brushes and rear brushes for passing current from said source through the rail, flaw responsive means positioned nearer to the rear brushes than to the front brushes, a normally ineffective auxiliary circuit through the rail in the region of said flaw responsive means, and means whereby said auxiliary circuit is rendered effective when the current between said front and rear brushes drops to a predetermined degree, said last-named means comprising a shunt circuit including a magnet and auxiliary brushes positioned between said front and rear brushes, said auxiliary circuit including said magnet, said auxiliary brushes, a pair of contacts, and means normally maintaining said contacts open to render said auxiliary circuit ineffective, means whereby said magnet closes said contacts when the current through said magnet exceeds a predetermined quantity and a resistance in said shunt circuit for maintaining the current through said magnet below said predetermined quantity as long as the current between said front and rear brushes exceeds a predetermined quantity.
